UNITED STATES PATENT OFFICE.

JULIUS H. HILDEBRANDT, OF CLEVELAND, OHIO.

OIL BURNER.

Application filed November 19, 1924. Serial No. 750,904.

To all whom it may concern:

Be it known that I, JULIUS H. HILDEBRANDT, a citizen of the United States, residing at Cleveland, in the county of Cuyahoga and State of Ohio, have invented a certain new and useful Improvement in an Oil Burner, of which the following is a full, clear, and exact description, reference being had to the accompanying drawings.

10 This invention relates to liquid fuel burners particularly those wherein the fuel is fed by gravity, and wherein air is supplied under pressure for supporting combustion.

One of the difficulties in operating oil burners of the forced draft type is the attainment of uniform distribution of fuel within the combustion zone. A further problem is to prevent the accumulation of a gummy substance which tends to stick to 20 the metal and to clog the fuel passageways.

One of the objects of the present invention, therefore, is the provision of an oil burner wherein the fuel distributing means is so arranged that the oil is caused to flow uniformly without necessitating the use of elongated closed passageways wherein gummy deposits may accumulate, and to so arrange the air conduit that the air for supporting combustion is caused to commingle 30 with the oil, and to flow through the passageways tending to maintain the passageways clear while the burner is in use.

A further object of my invention is the provision of an oil burner which may be readily installed in furnaces having a comparatively small combustion space, and which when once installed may be readily dismantled for cleaning purposes through the usual fire door opening. In addition, I 40 provide a burner which requires very little machine work to effect proper coordination of the component parts.

The preferred means for carrying out my invention is illustrated in the accompanying drawings wherein Fig. 1 is a vertical section through a portion of a furnace showing my invention installed therein; Fig. 2 is a perspective view of the fuel distributor; Fig. 3 is a transverse section through the distributor, and Fig. 4 is a vertical section through a portion of a furnace showing a modification of my burner.

55 My invention is illustrated within a furnace, the walls of which are indicated at 10 and the base of which is illustrated at 11. A grate 12 is disposed across the top

of the base and represents any suitable or convenient form of grate. An opening 13 in the base may comprise the usual opening for the ash pit door, while an opening 14 in 60 the furnace wall indicates the opening for the fire box door. The burner is adapted to be positioned upon the grate and is arranged to be inserted through the fire box door opening for assembling purposes. The 65 conduits through which the fuel and air are admitted are preferably arranged to be led through the ash pit door opening.

The burner illustrated in Fig. 1 has a central air conduit which extends through 70 the grate. This conduit is shown as embodying a plurality of sections 17, 18 and 19 which communicate with an air supply pipe 16. An oil supply conduit 20 extends through the air conduit and is arranged to 75 be attached at the upper end thereof to an oil distributor indicated at 21. This distributor preferably rests upon the uppermost edge of the air conduit and has openings 22 for allowing the passage of air therethrough. 80

The fuel distributor has spaced passageways 22 which extend downwardly from the top 23 of the distributor and terminate adjacent vertical passageways 24 for enabling oil to drop upon the outer surface of the 85 section 17.

To effect intermingling of the air and oil and at the same time to utilize the action of a moving current of air for preventing the accumulation of gummy deposits upon the 90 distributor, I employ a hood 25. The hood may be supported upon the distributor by spaced ribs 26, as shown in Fig. 1. This permits the hood to be lifted from the distributor through the fire door opening and 95 thus renders the distributor readily accessible for cleaning purposes.

To deflect the commingled air and fuel into the furnace, I have shown in Fig. 1 a conical baffle 30 which has a trough 31 at the base thereof for holding a small quantity of fuel which may be ignited for heating the burner before the fuel is turned on. The sloping sides of the conical baffle function to effect a thorough intermingling of 100 air and fuel on all sides of the burner. To deflect the fuel and air laterally into the combustion zone, I have shown a baffle indicated in Fig. 1 at 29 beneath the conical baffle and above a base 32. The base is arranged to rest upon the grate and to have an 105 upwardly extending flange 33 which forms 110

the intermediate section of the air conduit and is arranged to support the baffle 30. The baffle 29 moreover has a central opening 34 for enabling overflow oil to enter a trough 35 in the base from which an overflow conduit 36 leads to a suitable oil supply cut-off mechanism (not shown).

One of the difficulties in the operation of an oil burner having air supplied under pressure is to prevent a gas pilot from being extinguished when the blower is in operation. I overcome this difficulty by employing a gas distributor, the openings from which extends in the same general direction as the air current. In the preferred form the gas distributor is formed integral with the oil distributor and embodies spaced passageways 40 which lead from the chamber 41 at the central part of the distributor and terminate in downwardly extending passageways 42. A supply conduit 43 is shown as connected at the top to the distributor so as to communicate with the chamber 41 and as enclosing the oil conduit 20.

To effect a satisfactory connection between the gas and oil conduits and the air conduit, without disturbing the oil distributor, I have shown the lower section 19 of the air conduit as having an enlarged opening 45 adjacent the bottom thereof through which the gas and oil conduits extend. A suitable fitting 46 may be threaded onto the gas pipe outside the lower section of the air conduit until a gas tight connection is made therewith. This fitting when drawn tightly against a washer 47 functions to clamp the air sections tightly together, whereby the oil distributor is maintained in level position, even though the burner should be jarred by impact of an object which may be thrown into the furnace.

The fitting 46 moreover provides a suitable means for receiving a gas supply conduit 48, and an oil supply conduit 49, which are shown as leading outwardly from the furnace through the ash pit door opening.

By making the oil distributor integral with the gas distributor, the position of the gas pilot is always maintained in proper relationship to the flow of oil. Moreover, by providing spaced notches adjacent the top of the baffle 30, then the arms 51 forming part of the gas distributor may enter these recesses and keep the distributor from rotating with reference to the baffle when the fitting 46 is threaded onto the conduit 43. This brings the distributor into close fitting engagement with the top of the baffle, wherefore air flowing through the burner is caused to pass through the openings 22 and to enter the hood. The air then passes downwardly across the top of the oil distributor and out between the hood and section 17. Some of the air will flow through the passageways 24, thereby functioning to main-

tain the passageways free from gummy deposits and to keep the burner operating at its highest efficiency.

To eliminate the necessity for a plurality of castings between the grate and the distributor, I have shown in Fig. 4, a single casting which embodies a conical baffle 30^a, a trough 31^a, and a laterally extending baffle 29^a. Refractory material such as fire brick 28 may then be disposed upon the shoulder or laterally extending baffle 29^a to deflect the flame into the combustion zone. A trough 35^a provides an overflow receptacle from which a conduit 36^a may lead to a drip bucket, (not shown). The distributor employed with the modified arrangement rests upon the top of the baffle 30^a and has the arms 51 which comprise the gas distributor disposed in notches 50. The distributor and hood construction is the same in the modified arrangement as that employed in Fig. 1. This simplifies the burner construction and facilitates the assembly thereof.

From the foregoing description it will be evident that I have provided an oil burner wherein the fuel is maintained comparatively cool until it is ejected into the combustion zone of the furnace, and wherein in the air for supporting combustion is caused to flow across and through the oil distributor and to maintain it in proper working condition.

A particular advantage of the arrangement illustrated by my invention is the fact that the oil distributor may be clamped firmly to the supporting baffle wherefore uniform distribution of fuel may be maintained after the burner is assembled.

I claim:

1. In combination, an air conduit, an oil distributor resting on said conduit, a fuel supply pipe extending through the air conduit and connected to the distributor, a hood positioned on the distributor, said distributor having openings therein for enabling air to flow from the conduit through the distributor, and said distributor having a plurality of spaced passageways for conducting air from the supply pipe to spaced points adjacent the marginal edges of the distributor, said hood being so spaced that a mixture of air and fuel is deflected downwardly over the distributor and around the outer side of the air conduit, a baffle associated with the air conduit for deflecting the combined mixture outwardly, said air conduit having an opening adjacent the bottom thereof, the fuel pipe extending through said opening, and a member threaded to the fuel pipe outside the air conduit, said member functioning to clamp the distributor, the air conduit, and the fuel supply pipe together, and said member providing a continuation of the fuel supply pipe.

2. In an oil burner, the combination with

an air conduit, of a fuel supply conduit extending through the center of the air conduit, a fuel distributor connected to the fuel supply conduit and in abutting engagement 5 with the top of the air conduit, a gas conduit also disposed within the air conduit, said distributor having a passageway leading from the oil conduit, and having another passageway leading from the gas conduit 10 whereby the oil and gas are caused to flow in the same general direction while being discharged from the distributor.

3. In an oil burner, the combination with an air conduit adapted to extend through a 15 grate, said conduit having a conical baffle associated therewith, and having a fuel receiving trough adjacent the base of the baffle, a fuel distributor rigidly connected to the top of the air conduit, gas and liquid fuel 20 supply conduits within the air conduit, and operatively connected to the distributor, spaced passageways within the distributor for directing the liquid fuel and gas to flow downwardly onto the baffle, said distributor 25 having an opening therein whereby air is caused to flow through the distributor, and a hood carried by the distributor for deflecting air downwardly whereby some of the air flows through the liquid fuel passageways 30 while the rest of the air flows around the gas passageways and onto said baffle.

4. In an oil burner, the combination with an air conduit, of an oil distributor rigidly mounted on the top of the air conduit, a 35 portion of said conduit extending downwardly to provide an oil trough, and extending laterally to provide a baffle support, a baffle of refractory material positioned

on the support, the upper surface of the refractory material extending approximately 40 on a level with the top of the support, and a hood positioned over the distributor for deflecting air downwardly and across said baffle.

5. A fuel distributor for an oil burner 45 comprising a member having a central opening through which oil may flow, spaced passageways leading downwardly and outwardly from the top of the opening and a gas passageway extending radially from the central opening, said gas passageway and oil passageways having the outlet ends thereof 50 extending in the same general direction whereby oil and gas moving therethrough are caused to flow in substantially the same 55 direction.

6. A distributor for an oil burner embodying a hollow member having a central opening, a gas pipe and an oil pipe communicating with the opening, an oil conduit extending to the top of the distributor, a plurality of spaced passageways leading from the oil conduit, there being openings in the member intermediate the passageways for enabling the passage of air therethrough 60 to support combustion, spaced arms extending radially from the central opening and having passageways therein, communicating with the gas conduit, the oil and gas passageways being so positioned with relation to 65 each other that oil and gas flowing respectively therethrough are caused to leave the distributor in the same general direction.

In testimony whereof, I hereunto affix my signature.

JULIUS H. HILDEBRANDT.
